Specification of Letters Patent. Patented Apr. 20, 1920.

Application filed October 17, 1918. Serial No. 253,505.

To all whom it may concern:

Be it known that we, RAY S. WILBUR and WILLIAM H. HARRISON, citizens of the United States, residing at Lyndhurst, in the county 5 of Bergen, State of New Jersey, and at Brooklyn, in the county of Kings, State of New York, respectively, have invented certain new and useful Improvements in Telephone Systems, of which the following is a 10 full, clear, concise, and exact description.

This invention relates to telephone systems and more particularly to such systems in which trunk lines common to a plurality of switchboards may be employed in establishing connections between telephone lines terminating at the various switchboards.

The object of this invention is to provide a system of this character in which a limited number of trunk lines may be more efficiently used to supply a large number of channels for telephone communication between the various switchboards connectible with the trunk lines.

In accordance with the various features of this invention, two trunk lines connecting together two widely separated switchboards pass through a plurality of intermediate switchboards, apparatus being provided at each intermediate switchboard by means of 20 which connection may be established between any telephone line terminating thereat and a switchboard in either direction over either trunk line or over a phantom circuit formed of the two trunk lines. Normally 25 the two trunk lines and the phantom circuit superposed thereon are looped through each intermediate switchboard, and when connection is made with either trunk line at any such switchboard, that trunk line is severed 30 at that switchboard and apparatus functions to maintain the continuity of the phantom circuit through that switchboard. Likewise, if connection be made with the phantom circuit at an intermediate switchboard, the 35 phantom circuit is severed at that switchboard and apparatus functions to maintain the continuity of both trunk lines through that switchboard.

For a more complete understanding of 40 this invention, reference should be had to the following description considered in connection with the accompanying drawings

illustrating one embodiment thereof, and in which Figure 1 shows two trunk lines joining two widely separated switchboards and 55 passing through a plurality of intermediate switchboards, the two trunk lines being phantomed at each of the terminal switchboards to provide a phantom circuit therebetween; Fig. 2 shows a telephone line of 60 the type terminating at the intermediate switchboards and a link circuit of the type employed for interconnecting telephone lines or for connecting a telephone line with either of the trunk lines or with the phantom 65 circuit; and Fig. 3 shows the organization of apparatus and circuits employed at each of the intermediate switchboards.

Referring more particularly to Fig. 1, 5 and 6 represent two trunk lines joining two 70 terminal switchboards A and B. The trunk line 5 terminates in a jack 7 at the switchboard A and in a jack 8 at the switchboard B, while the trunk line 6 terminates in a jack 9 at the switchboard A and in a jack 10 75 at the switchboard B. In order that a phantom circuit between the terminal switchboards may be superimposed upon the trunk lines 5 and 6, repeating coils 11 are connected in each trunk line at each of the terminal switchboards. This phantom circuit terminates at the switchboard A in a jack 12 connected to the middle points of windings of the repeating coils 11, 11 thereat, while at the switchboard B the phantom 80 circuit terminates in a jack 13 similarly connected to the middle points of the repeating coils 11, 11 thereat. Associated with each of the jacks is a ring-up relay 14 which is energized by means of ringing current incoming 85 over the respective trunk line or phantom circuit, and when energized locking up through the lower normal contact of the jack and the contact of the relay thereby to light a line lamp 15, and maintains the lamp 90 lighted until connection is made with the corresponding jack, whereby the normal contacts of the jack are opened to release and disconnect the relay from the line and to extinguish the lamp. In Fig. 1 the apparatus shown to the left of dotted line 2-2 is located at the switchboard A, while that shown to the right of the dotted line 3-3 95 is located at the switchboard B.

As hereinbefore stated, the trunk lines 5 and 6 and the phantom circuit superimposed thereupon are looped through a plurality of intermediate switchboards. In Fig. 1 these 5 are represented by the letters X, Y and Z. All of these intermediate switchboards are identically equipped.

- The circuits and apparatus of an intermediate switchboard associated with the 10 trunk lines and phantom circuit are shown in Fig. 3, while in Fig. 2 there are shown a telephone line C representing the type of telephone line terminating at each of the intermediate switchboards and a cord circuit 15 D representing the type of cord circuit employed at each of the intermediate switchboards for interconnecting telephone lines and for connecting telephone lines with the trunk lines and the phantom circuit.
- 20 The trunk lines and the phantom circuit are normally looped through each of the intermediate switchboards without being connected with any of the apparatus thereat. For example, trunk line 5 enters an intermediate 25 switchboard from the left, through the normal contacts of relay 20 and extending over conductors 21 and 22 and passing from the intermediate switchboard through the normal contacts of relay 23 and then on 30 to the next switchboard. In like manner, trunk line 6 enters an intermediate switchboard through the normal contacts of relay 24, extending therethrough over conductors 25 and 26 and out through the normal contacts 35 of relay 27. In order that connection may be made with either of the trunk lines or with the phantom circuit at an intermediate switchboard, there are associated with the trunk line 5 a jack 30 for establishing connection therewith in one direction and a jack 31 for establishing connection therewith in the other direction; with the trunk line 6, a jack 32 for establishing connection therewith in one direction, a jack 33 for establishing connection therewith in the other direction; and with the phantom circuit a jack 34 for establishing connection therewith in one direction and a jack 35 for establishing connection therewith in the other direction.
- 40 Jacks 36 and 37 associated with the trunk lines 5 and 6 respectively and a jack 38 associated with the phantom circuit are test jacks by means of which the operator thereat, upon connecting the cord circuit D therewith and actuating the listening key, may bridge the operator's telephone set across the corresponding trunk line or phantom circuit to determine whether the particular trunk line or phantom circuit is idle 45 or busy.
- 50 In order that the continuity of the phantom circuit through an intermediate switchboard may be maintained when connection thereat is made with either of the trunk lines, repeating coils are associated with

each of the connection jacks for the trunk lines. These repeating coils perform the further function of connecting the jack terminals with the trunk line. One side of each of these repeating coils 40 is connected with the tip and ring contacts of the associated jack, while the other side thereof is connected to normally open contacts of the associated switching relay through whose normal contacts the trunk line enters or 70 leaves the intermediate switchboard. There is associated with each of the phantom circuit jacks 34 and 35 a repeating coil 41, one side of which is connected to the tip and ring contacts of the associated jack and the other side of which is connected to normally open contacts of a switching relay. The repeating coil associated with jack 34 is connected with the normally open contacts of switching relay 42, and the repeating coil 80 associated with jack 35 is connected with the normally open contacts of switching relay 43.

In order that the operator at an intermediate switchboard may be signaled over 90 either of the trunk lines or over the phantom circuit, telephone call bells of the usual construction are associated with the trunk lines and phantom circuit. Call bell 45 is normally bridged across looping conductors 95 21 and 22 of the trunk line 5 through normally closed contacts 46 and 47 of a switching relay 48, while call bell 46 is normally bridged across the looping conductors 25 and 26 of the trunk line 6 through normally closed contacts 49 and 50 of a switching relay 51. A call bell 52 is normally bridged across the phantom circuit through the normally closed contacts of a switching relay 53, normally closed contact 54 of switching 100 relay 51 and normally closed contact 55 of switching relay 48, the bridge including this call bell 52 being connected to one side of the phantom circuit through the windings of retardation coil 56 and with the other side through the windings of retardation coil 57. A retardation coil 58 is connected in series with each of the call bells to increase the impedance of the bridge whereby the several bridges are made of high impedance to talking currents.

The cord circuits D employed at the intermediate switchboards are of the universal type, so that they may be used for interconnecting local common battery telephone 115 lines terminating thereat, or for connecting a telephone line with either of the trunk lines or the phantom circuit, or for connecting either of the trunk lines or the phantom circuit with a telephone line. Each 120 end of the cord circuit D is similarly equipped. The apparatus associated with the left end of the cord circuit will be designated by reference numbers without primes and corresponding apparatus associated 125 130

65 lines, repeating coils are associated with

with the right end of the cord circuit will be designated with the same reference numbers with primes.

- A relay 80 is normally bridged across the 5 talking strands and may be energized by ringing current incoming to the intermediate station when the cord circuit is connected with either a trunk line or a phantom circuit. Each end is also provided with 10 a supervisory relay 81 which functions to control a supervisory lamp 82 on common battery connections, and coöperates with the bridged relay 80 when controlled over either of the trunk lines or the phantom 15 circuit to maintain a locking circuit through the lamp 82, for purposes of supervision. A relay 83 in each end of the cord circuit for controlling a contact in the circuit of the supervisory lamp 82 operates when the 20 cord circuit is connected with either a telephone line, a trunk line or with the phantom circuit. In series with the relay 83 is a marginal relay 84 which operates when connected in circuit with the low resistance 39 25 of the common battery telephone line, but does not operate when connected in circuit with the high resistance of the various sleeve relays associated with the connecting jacks of the trunk lines and the phantom 30 circuit. Each end of the cord circuit is equipped with a ringing key 85, and a listening key 63 is provided by means of which the operator's telephone set may be connected in circuit.
- 35 If plug 60 of the cord circuit is connected with the telephone line C, relays 83 and 84 operate. If the receiver is off the switchhook the supervisory relay 81 is operated, preventing the lighting of the lamp 82.
- 40 The restoration of the receiver to the switchhook causes the lamp 82 to be lighted over a circuit from battery through the lower alternate contact of marginal relay 84, normal contact of supervisory relay 81, 45 contact of relay 83, and upper normal contact of listening key 63 to ground. If the plug 60 is connected with the connecting jack of either a trunk line or the phantom circuit, relay 83 operates, but marginal relay 84 does not operate. The energization 50 of the bridged relay 80, by ringing current incoming to the intermediate switchboard, causes the operation of supervisory relay 81 over a circuit from battery through the winding of relay 81, contact 86 of relay 84, 55 resistance 87, contact of bridged relay 80, contact of relay 83, lamp 82 and the upper normal contact of listening key 63 to ground. Relay 81 in operating connects its 60 alternate contact in bridge of the contact of relay 80, thereby establishing a locking circuit for relay 81. The lamp 82 is maintained lighted over this circuit until the listening key 63 is actuated or relay 83 released. The apparatus associated with the

other end of the cord circuit functions in identically the same manner when the plug 62 is employed to connect a cord circuit with a telephone line, a trunk line or the phantom circuit.

If the operator at an intermediate switchboard desires to establish a connection over the trunk line 5 in the direction of the terminal switchboard A, the plug 60 of the cord circuit D is first inserted into the jack 70 36 and the listening key 63 is actuated in order that the operator may determine whether this trunk line is idle or busy. If found to be idle, the plug 60 is withdrawn from the jack 36 and inserted into the jack 80 30, whereupon sleeve relay 61 is operated over a circuit from battery through the winding of marginal relay 84, the winding of relay 83, sleeve contacts of the plug 60 and the jack 30 and the winding of relay 61 85 to ground. Switching relays 20 and 23, 24 and 27 and 48 and 51 thereupon operate. The operation of switching relays 20 and 23 interrupts the normal continuity of the trunk line 5 and connects the respective sections of this trunk line to the windings of the repeating coils 40 associated with the jacks 30 and 31. The continuity of this trunk line 5 is not reestablished because the normal contacts of jack 30 are opened when 90 the plug 60 is inserted therein. The operation of switching relays 24 and 27 interrupts the normal continuity of the trunk line 6 but immediately reestablishes the continuity thereof by way of the repeating coils 100 40 and the normal contacts of the associated jacks 32 and 33. The operation of switching relay 48 disconnects the call bell 45 from the looping conductors 21 and 22 and bridges it across that end of the trunk line 105 5 which extends toward the switchboard B, while the operation of the switching relay 51 disconnects the call bell from the looping conductors 25 and 26 and connects it across the conductors joining the windings 110 of the repeating coils 40 associated with the trunk line 6. It will be seen, therefore, that the call bell 46, through the operation of switching relay 51 is bridged across the trunk line 6. The operation of the switching 115 relays 48 and 51 also connects the phantom circuit call bell 52 in bridge of conductors 66 and 69 forming a part of an alternate looping circuit for the phantom circuit established when connection is made 120 with either trunk line.

While the trunk line 5 has been divided into sections as a result of plugging into the jack 30, the continuity of the trunk line 6 has been maintained, and, as will now more 125 fully appear, the continuity of the phantom is also maintained. The upper leg of the phantom circuit through the intermediate switchboard may be traced from the alternate contacts of switching relay 20 in paral- 130

lel through the left-hand windings of the connected repeating coil 40 in parallel, conductor 65, upper normal contact of switching relay 42, conductor 66, upper normal contact of switching relay 43, conductor 67, 5 right-hand windings of repeating coil 40 in parallel and the alternate contacts of the associated switching relay 23 in parallel. Likewise the lower leg of this phantom circuit may be traced from the alternate contacts of switching relay 24 in parallel 10 through the left-hand windings of the associated repeating coil 40 in parallel, conductor 68, lower normal contact of switching relay 42, conductor 69, lower normal contact of switching relay 43, conductor 70, 15 right-hand windings of repeating coil 40 in parallel and the alternate contacts of switching relay 27 in parallel.

20 After the insertion of the plug 60 into the jack 30, the operator at the desired switchboard may be signaled by actuating a ringing key 85 which impresses ringing current on the trunk line 5 and causes the 25 operation of the call bell 45 at the appropriate intermediate station, or the operation of the relay 14 at the terminal switchboard A. In signaling an intermediate switchboard a code may be employed in order 30 that the operator at each switchboard may determine whether that particular switchboard is desired and to determine whether the trunk line 5, the trunk line 6 or the phantom circuit is to be connected 35 with.

If the operator at the intermediate switchboard had desired to make connection with trunk line 5 in the direction of the terminal switchboard B, the plug 60 would then have 40 been inserted into the jack 31. Relay 72 would then operate, causing the operation of switching relays 20, 23, 24, 27, 48 and 51 in the manner above described. If connection had been made with the jack 32, 45 associated with the trunk line 6, sleeve relay 73 associated therewith would then have operated, whereupon the switching relays would function, as previously described, and if connection had been made with the jack 50 33, sleeve relay 74 would have operated, causing the operation of the same switching relays.

If the operator at an intermediate switchboard should desire to establish a connection 55 over the phantom circuit in either direction, the busy or idle condition of the phantom circuit would first be determined by inserting the plug 60 in the jack 38. If the phantom circuit is idle and connection 60 is to be established thereover in the direction toward the terminal switchboard A, the plug 60 is inserted into the jack 34, whereupon sleeve relay 75 operates, causing the operation of switching relays 20 and 23, 65 which interrupts the normal continuity of

the trunk line 5 but immediately reestablishes it through an alternate path including the normally closed contacts of the jacks 30 and 31 and the windings of the associated repeating coil 40. Switching relays 70 24 and 27 also operate to interrupt the normal continuity of the trunk line 6 and to reestablish it through an alternate path including the normally closed contacts of the jacks 32 and 33 and the windings of the 75 associated repeating coil 40. Switching relays 48 and 51 also operate to connect the call bells 45 and 46 in bridge of the respective alternate looping conductors by means of which the continuity of the trunk lines 80 5 and 6 is maintained. Phantom circuit switching relays 42, 43 and 53 also operate upon the energization of sleeve relay 75. Relay 42 in operating interrupts the continuity of the phantom circuit at its normal 85 contacts and connects that portion of the phantom circuit extending toward the terminal switchboard A with the left-hand windings of the repeating coil 41, whereby this end of the phantom circuit is terminated at 90 the intermediate switchboard at which connection is made with the jack 34. The operation of the switching relay 43 likewise terminates the portion of the phantom circuit extending toward the switchboard B at 95 the jack 35 of the intermediate switchboard. The operation of switching relay 53 bridges the phantom circuit call bell 52 across the phantom circuit extending toward the switchboard B. If connection had been 100 made with the phantom circuit of jack 35, relay 76 would then operate, causing the operation of the same switching relays as are operated by the energization of the sleeve 105 relay 75 except relay 53, the energizing circuit of which is not established upon the energization of relay 76. In this case, however, the call bell 52 would be bridged across the phantom circuit extending toward the 110 switchboard A.

From the above description it will be evident that this invention contemplates a system employing two trunk lines upon which is superimposed a phantom circuit, which join terminal switchboards and are looped through a plurality of intermediate switchboards at each of which is provided apparatus for establishing connection with either of the trunk lines or the phantom circuit in either direction. Furthermore, it will be 115 apparent that when connection is made with either trunk line in either direction at an intermediate switchboard, the continuity of that trunk line is interrupted at the particular intermediate switchboard and the call bell normally bridged thereacross is connected with that portion extending in the opposite direction and the normal continuity of the phantom circuit is interrupted but is immediately reestablished through an 120 125 130

alternate path, and the phantom circuit call bell is also connected across the alternate path. When connection is made at an intermediate switchboard with the phantom circuit in either direction, the continuity of the through phantom circuit is interrupted and apparatus functions automatically to divide the original phantom circuit into two phantom circuits. In fact, each trunk line 5 may be divided into as many separate trunk lines as there are sections between switchboards and, in a similar manner, the original through phantom circuit may be split up 10 into as many phantom circuits as there are 15 sections between switchboards.

What is claimed is:

1. In a telephone system, in combination, two trunk lines joining two widely separated switchboards and looped through an intermediate switchboard, apparatus at each terminal switchboard for phantoming the two trunk lines thereby providing a phantom circuit over the trunk lines between the terminal switchboards, telephone lines terminating 20 at the intermediate switchboard, a link circuit for establishing connection between a telephone line and one of the trunk lines, and means responsive to the connection of the link circuit with one end of a 25 trunk line for interrupting the continuity thereof between the terminal switchboards and for maintaining the continuity of the 30 phantom circuit therebetween.

2. In a telephone system, in combination, two trunk lines joining two widely separated switchboards, apparatus at each switchboard for phantoming the trunk lines thereby providing a phantom circuit between the switchboards, an intermediate 35 switchboard, circuit leads thereat normally maintaining the continuity of the trunk lines and the phantom circuit, telephone lines terminating at the intermediate switchboard, a link circuit thereat for connecting the telephone lines with the trunk lines, apparatus responsive to the connection of the link circuit with one trunk line to interrupt the normal continuity of both trunk lines and the phantom circuit, and other circuit leads 40 45 terminating at the intermediate switchboard, a link circuit thereat for connecting the telephone lines with the trunk lines, apparatus responsive to the connection of the link circuit with one trunk line to interrupt the normal continuity of both trunk lines and the phantom circuit, and other circuit leads 50 55 terminating at the intermediate switchboard, a link circuit thereat for connecting the telephone lines with the trunk lines, apparatus responsive to the connection of the link circuit with one trunk line to interrupt the normal continuity of both trunk lines and the phantom circuit, and other circuit leads 60 65 terminating at the intermediate switchboard, a link circuit thereat for connecting the telephone lines with the trunk lines, two sets of terminals for each trunk line at the intermediate switchboard.

mediate switchboard normally disconnected therefrom, a repeating coil connected with each set of terminals, means responsive to the connection of the link circuit with one set of terminals of one trunk line for 70 connecting one end thereof with the associated repeating coil and for interrupting the normal continuity of both trunk lines and the phantom circuit, and other circuit leads including the repeating coils thereupon rendered effective for maintaining the continuity of the other trunk line and the phantom circuit.

4. In a telephone system, in combination, two trunk lines joining two widely separated switchboards, apparatus at each switchboard for phantoming the trunk lines thereby providing a phantom circuit between the switchboards, an intermediate switchboard, circuit leads thereat normally 80 maintaining the continuity of the trunk lines and the phantom circuit, telephone lines terminating at the intermediate switchboard, a link circuit thereat for connecting the telephone lines with the trunk lines and the phantom circuit, apparatus responsive to the connection of the link circuit with the phantom circuit for interrupting the normal continuity of both the trunk lines and the phantom circuit, and 85 other circuit leads thereupon rendered effective for maintaining the continuity of both trunk lines.

5. In a telephone system, in combination, two trunk lines joining two widely separated switchboards, apparatus at each switchboard for phantoming the trunk lines thereby providing a phantom circuit between the switchboards, an intermediate switchboard, circuit leads thereat normally 100 maintaining the continuity of the trunk lines and the phantom circuit, telephone lines terminating at the intermediate switchboard, a link circuit thereat for connecting the telephone lines with the trunk lines and the phantom circuit, apparatus responsive to the connection of the link circuit with the phantom circuit for interrupting the normal continuity of both the trunk lines and the phantom circuit, and 105 other circuit leads thereupon rendered effective for maintaining the continuity of both trunk lines.

6. In a telephone system, in combination, two trunk lines joining two widely separated switchboards, apparatus at each switchboard for phantoming the trunk 110 lines and the phantom circuit, apparatus responsive to the connection of the link circuit with the phantom circuit for interrupting the normal continuity of both the trunk lines and the phantom circuit, a plurality of repeating coils, circuit leads including the repeating coils thereupon rendered effective for terminating each portion of the phantom circuit at the intermediate switchboard thereby dividing the original phantom circuit into two phantom circuits, and other circuit leads including several of the repeating coils rendered effective upon the response of the apparatus for maintaining the continuity of the trunk lines.

7. In a telephone system, in combination, two trunk lines joining two widely separated switchboards, apparatus at each switchboard for phantoming the trunk 115 lines and the phantom circuit, apparatus responsive to the connection of the link circuit with the phantom circuit for interrupting the normal continuity of both the trunk lines and the phantom circuit, a plurality of repeating coils, circuit leads including the repeating coils thereupon rendered effective for terminating each portion of the phantom circuit at the intermediate switchboard thereby dividing the original phantom circuit into two phantom circuits, and other circuit leads including several of the repeating coils rendered effective upon the response of the apparatus for maintaining the continuity of the trunk lines.

lines thereby providing a phantom circuit between the switchboards, an intermediate switchboard, circuit leads thereat normally maintaining the continuity of the trunk lines and the phantom circuit, a signal receiving device for each of the trunk lines and the phantom circuit normally connected with the circuit leads, telephone lines terminating at the intermediate switchboard, a link circuit thereat for connecting the telephone lines with the trunk lines, switching apparatus responsive to the connection of the link circuit with one end of one trunk line to interrupt the normal continuity of both trunk lines and the phantom circuit, other circuit leads thereupon rendered effective for maintaining the continuity of the other trunk line and the phantom circuit, and switching apparatus for connecting the signal receiving devices with the other circuit leads.

7. In a telephone system, in combination, two trunk lines joining two widely separated switchboards, apparatus at each

switchboard for phantoming the trunk lines thereby providing a phantom circuit between the switchboards, an intermediate switchboard, circuit connections thereat normally maintaining the continuity of the trunk lines and the phantom circuit, telephone lines terminating at the intermediate switchboard, a link circuit thereat for connecting the telephone lines with the trunk lines, switching relays energized upon the connection of the link circuit with one trunk line to interrupt the normal continuity of both trunk lines and the phantom circuit, and other circuit connections including inductive devices for maintaining the continuity of the other trunk line and the phantom circuit.

In witness whereof, I hereunto subscribe my name this 19th day of August, 1918.

RAY S. WILBUR.

In witness whereof, I hereunto subscribe my name this 2 day of Oct., 1918.

WILLIAM H. HARRISON.
